UNITED STATES PATENT OFFICE.

CHARLES POTTICARY, OF ST. THOMAS, ONTARIO, CANADA.

TURBINE-DRIVEN LOCOMOTIVE.

No. 880,163.

Specification of Letters Patent.

Patented Feb. 25, 1908.

Application filed June 22, 1907. Serial No. 380,283.

To all whom it may concern:

Be it known that I, CHARLES POTTICARY, a citizen of the United States, residing at St. Thomas, in the Province of Ontario, Dominion of Canada, have invented certain new and useful Improvements in Turbine-Driven Locomotives; and I do hereby declare the following to be a full, clear, and exact description of the invention, such as will 5 enable others skilled in the art to which it appertains to make and use the same.

The present invention has reference to locomotives adapted to be propelled by an elastic fluid turbine mounted on the main 15 frame of the locomotive, and it aims, broadly, to provide a powerful and durable, as well as highly efficient engine of the above-mentioned type in which the turbine shaft is directly connected with the front and rear 20 drivers, and in which the admission of the elastic fluid to the turbine is positively under the control of the engine, whereby the engine may be started and stopped and the direction of rotation of the turbine readily and 25 quickly reversed.

With the above and other ends in view, the invention consists in the construction, combination, and arrangement of parts, all as hereinafter more fully described, specifically claimed, and illustrated in the accompanying drawings, in which like parts are designated by corresponding reference numerals in the several views.

Of the said drawings—Figure 1 is a side 35 elevation of a turbine-driven locomotive constructed in accordance with the present invention. Fig. 2 is a top plan view thereof, a part of the casing of the turbine being broken away. Fig. 3 is a rear elevation. Fig. 4 is a longitudinal vertical section. Figs. 5 and 6 are transverse sections taken on the lines 5—5 and 6—6 of Fig. 1. Fig. 7 is an enlarged detail view of one of the turbine 40 wheels. Fig. 8 is an enlarged fragmental view of the steam chest, illustrating the disposition of the compound reversing lever and valves therein, and the pipe connections between the steam chest, turbine, and throttle chamber. Fig. 9 is a perspective view of one 45 of the valves carried by the reversing lever. Fig. 10 is a detail view of the reversing lever and its connections.

Referring more particularly to the drawings, 1 designates the main frame of the locomotive, 2 the front truck, and 3 and 4 the front and rear drivers mounted, respectively, upon the front and rear axles 5 and 6 journalled at opposite ends in bearings se-

cured to the under face of the main frame, which latter carries a horizontal boiler 7 provided with a steam-chest 9 and a throttle chamber 8.

The throttle chamber, above referred to, which is provided with a lever 10 to which the stem of a cutoff valve 11 is pivoted, is connected by a pipe 12 with the steam-chest, and by a second pipe 13 with the interior of a housing 14, in which a turbine 15 is rotatably mounted upon a shaft 16, said shaft projecting at opposite ends through openings formed in the side walls of the housing and being journaled at such points in 70 bracket bearings 17, the housing and brackets being bolted or otherwise secured to the boiler.

At its rear end, the turbine shaft carries a sprocket 18 connected by a chain 19 with a sprocket 20 secured to the projecting outer end of a worm shaft 21, which worm shaft or stoker is disposed in the rear compartment of the fire-box 22 located at the rear end of the main frame and beneath the boiler, the coal, which is forced by the stoker into the fire-box, being fed to the stoker from a hopper 23 which communicates directly with the stoker compartment and is located below the fire-door 24.

The upper wall of the fire-box is perforated in the usual manner for the reception of the lower ends of the flues 25, which extend longitudinally within the boiler chamber, each flue comprising an upper section and a lower section which are disposed in the corresponding compartments into which the boiler chamber is divided by a horizontal, longitudinally-extending partition plate 26, said plate terminating short of the forward 90 end of the boiler chamber, as shown in Fig. 4. The products of combustion will therefore pass through the perforations in the upper wall of the fire-box, and from thence through the flues, the free ends of the upper sections 95 of which are disposed directly beneath the smoke stack 27, which is located at the rear end of the boiler, the bent construction of the flues causing the products of combustion to pass twice from end to end of the boiler 100 chamber prior to their discharge through the smoke stack. Four of the flues, however, are continued through the rear end of the boiler and are directed downwardly, as indicated by the reference numeral 28, and are 105 finally led through the stoker chamber, as at 29, to a point directly beneath the grate 30 of

the fire-box, whence the products of combustion carried therethrough will be forced upwardly through the grate openings.

The exhaust steam from the turbine is discharged through a pipe 31 directly across the ash-pan disposed within the fire chamber beneath the grate 30, said pipe being connected at its upper end with the turbine housing and having its opposite end led through

10 an opening formed in the adjacent side wall of said chamber.

The admission of steam into the housing will therefore directly effect the rotation of the turbine, as will be understood, which 15 movement will be transmitted through the chain and sprocket connection above described, to the stoker shaft by which the fuel is fed into the fire-box, the exhaust steam being discharged across the ash-pan as stated.

20 Disposed between the drivers 3 and 4 and journaled at opposite ends in brackets 32 bolted to the main frame and to the boiler, is a transverse shaft 33, which carries a pair of turbine wheels 34, arranged side by side 25 and incased by a two-part housing 35, which is likewise bolted to the boiler. Each section of this two-part housing is provided with a pair of inlet ports 36 and 37, and with an outlet port 38, while the steam-chest has 30 formed in its top at each side a pair of outlet ports 39 and 40, and towards its bottom a pair of inlet ports 41. The inlet port 36 of each housing section is connected by a long pipe 42 with the corresponding steam-chest

35 port 39, while its inlet pipe 37 is connected by a short pipe 43 with the port 40, the corresponding ports 38 and 41 being connected by the pipes 44 through which the dead-steam is exhausted from the turbines. The

40 steam-chest, moreover, is provided with a reversing mechanism, by means of which the direction of rotation of the turbines may be changed at will, to start or back the locomotive, such mechanism comprising a rear-

45 wardly-extending angle-lever 45, which is pivoted at its forward end to a rock-shaft 46, journaled in brackets secured to the steam-chest, said rock-shaft being provided towards its opposite ends with a pair of laterally-pro-

50 jecting brackets having bifurcated outer ends in which the stems 47 of a pair of cutoff valves 48 are pivoted. Each cutoff valve which is slidably fitted in a seat formed in the upper portion of the steam-chest, is pro- 55 vided with a pair of openings 49 and 50, formed transversely therethrough, and with a laterally-projecting tongue 51 disposed between said openings and adapted to close one or the other of a pair of outlet channels

60 53 and 54. When, therefore, the reversing lever is swung in one direction both ports or openings 54 will be covered by the tongues 51, the live steam passing, in consequence, through the openings 53, the forward open- 65 ings 49 in the cutoff valves and the ports 40

in the steam-chest, out through the short pipes 43 to the inlet ports 37 in the turbine housing, and thence directly against the turbines, reversing their motion and stopping or backing the locomotive. Movement of 70 the reversing lever in the opposite direction will cause the valve tongues to cover the openings 53 and uncover the openings 54, when the steam will be free to pass out through the rear ports 50 in the valves, and 75 the ports 39 in the steam-chest, and through the long pipes 42 and ports 36 to the turbines, rotating the latter in their normal direction, to move the locomotive forwardly. The reversing lever is held in adjusted position 80 by a pawl and rack mechanism of any conventional type.

The transverse shaft 33, upon which the turbine wheels are mounted, is further provided at opposite ends with a pair of drivers 85 55, which are disposed directly between the corresponding front and rear drivers 3 and 4. Each of the several drivers above referred to, has formed upon its outer face an enlarged hub portion 56, whose periphery is provided 90 with a series of concentric annular grooves 57, said grooves being adapted for the reception of the loops of the driving cables 58, the forward end of each cable passing around an idler 59 carried by the pilot 60, the brackets 95 in which the idlers are mounted being movable endwise in their bearings, to tighten or loosen the cables.

In positioning the driving cables, they are passed over the hubs of the upper drivers 55, 100 and around the hubs of the front and rear drivers 3 and 4 in opposite directions, as shown, the several loops crossing each other. The rotation of the upper drivers, carried on the turbine shaft will therefore effect the rotation of the lower or front and rear drivers, and, in consequence, the propulsion of the 105 locomotive.

The turbine 15 disposed within the housing 14 and one of the turbines 34 within the 110 housing 35 are preferably simple, while the other turbine 34 is of the compound type, although it is to be understood that all may be of either type, according as desired. The simple turbine, as shown in Fig. 7, is provided with a series of diagonally extending peripheral steam ports 60, between which are interposed the packing rings 61 and headers 62, each of which fits in a correspondingly shaped seat formed in the periphery of the 115 wheel, said rings and headers being normally held in raised position by means of springs 63 interposed therebeneath within the corresponding seats, the springs forcing the rings and headers yieldingly upward. Escape of 120 steam from one of said ports to another, and from one of the turbine wheels 34 to the other, is thus prevented, as the fittings of the rings and headers are steam tight, as will be 125 understood.

It will be apparent from the foregoing that the supply of steam to the turbines is positively under the control of the engineer, who is thus enabled to start and stop the locomotive, and effect its propulsion backwards or forwards at will. The reverse and throttle levers, which control the admission of steam to the turbines are provided with cable or link connections which extend rearwardly, to 10 within reach of the engineer within the cab, but no specific description or illustration of said elements has been thought necessary in view of the fact that they are of the ordinary type and common to all locomotives. The 15 cab is likewise of the conventional type and therefore requires no further description.

Although the invention has been shown and described as applied to a locomotive, it is to be understood that the turbines may be 20 utilized for driving any type of traction vehicle.

What is claimed, is—

1. In a turbine-driven traction vehicle, the combination with a frame and a plurality of 25 driving wheels carried thereby, of a boiler mounted upon the frame; a turbine mounted upon the boiler, and disposed transversely thereof between said driving wheels, the shaft of said turbine carrying a driving wheel at 30 each end; belt connections between the hubs of the first and last mentioned driving wheels; and means for controlling the supply of pressure medium to said turbine.

2. In a turbine-driven traction vehicle, the 35 combination with a frame and a plurality of driving wheels carried thereby, each of said driving wheels having an enlarged hub formed on its outer face and provided with a plurality of peripheral grooves, of a boiler 40 mounted upon the frame; a turbine mounted upon the boiler and disposed transversely thereof between said driving wheels, the shaft of said turbine carrying a driving wheel at each end, each of said last-mentioned 45 driving wheels having a grooved, enlarged hub similar to those formed on said first-mentioned driving wheels; a cable connection between each set of driving wheels, the loops of each cable being seated in the grooves in 50 each hub and crossing each other in their passage from one hub to another; and means for controlling the supply of pressure medium to said turbine.

3. In a turbine-driven traction vehicle, the 55 combination, with a frame and a plurality of driving wheels carried thereby, of a boiler mounted upon the frame; a turbine mounted upon the boiler and disposed transversely thereof between the wheels, said turbine in- 60 cluding inlet and exhaust pipes; a steam chest communicating with said inlet pipes;

means for controlling the supply of steam to said steam-chest; a driving wheel carried upon each end of the turbine shaft; and a cable connection between the hub of each of 65 said last-mentioned driving wheels and the hubs of the adjacent driving wheels carried by said frame.

4. In a turbine-driven traction vehicle, the combination, with a frame and a plurality of 70 driving wheels carried thereby, of a boiler mounted upon the frame; a housing mounted upon the boiler between the driving wheels; a pair of turbine wheels mounted side by side within the housing, each turbine having a 75 pair of inlet pipes and an outlet pipe communicating therewith at one end; a steam-chest mounted upon the boiler and provided with a series of ports in which the opposite 80 ends of said inlet pipe are fitted; a pair of cut-off valves slidably engaged in said steam chest; means for operating said cutoff valves simultaneously to direct the flow of steam through one or the other of each pair of inlet 85 pipes, to rotate the turbine wheels in one direction or the other; a driving wheel carried upon each end of the turbine shaft; and a cable connection between the hub of each of 90 said last-mentioned driving wheels and the hubs of the adjacent driving wheels carried by said frame.

5. In a turbine-driven locomotive, the combination with a frame and front and rear driving wheels carried thereby, of a 95 boiler disposed upon the frame; a housing mounted upon the boiler between the driving wheels; a turbine disposed within the housing transversely of the boiler and provided with a pair of inlet pipes and an exhaust pipe 100 communicating therewith at one end; a steam-chest mounted upon the boiler and provided with a series of ports in which the opposite ends of said inlet pipes are fitted; a throttle chamber mounted upon the boiler in communication with the steam-chest; reversing mechanism carried by the steam-chest for directing the flow of steam into one or the other of said inlet pipes, to change the direction of rotation of the turbine; a turbine mounted upon the frame at the rear end 110 thereof; a screw-conveyer disposed within the fire-box of the locomotive; and driving connections between the shaft of said conveyer and the shaft of the last-mentioned 115 turbine.

In testimony whereof, I affix my signature, in presence of two witnesses.

CHARLES POTTICARY.
